---

I, ROBERT G. CLEMONS, of the city of Nashua, county of Hillsborough and State of New Hampshire, have invented and produced a new and original "Design for Spool-Stands," of which the following is a specification.

The nature of my design is fully represented in the accompanying photographic illustration, to which reference is made.

My design consists in the use of an ornamental saucer-like shelf or receiver A, for the purpose of

holding thimbles, scissors, or other implements of needle-work.

I claim as my invention—

The design for a spool-stand, with ornamental shelf or receiver, as shown.

R. G. CLEMONS.
